UNITED STATES PATENT OFFICE.

JESSE PRESCOTT, OF WEBSTER, MASSACHUSETTS.

GARBAGE-INCINERATOR.

1,093,356.

Specification of Letters Patent. Patented Apr. 14, 1914.

Application filed March 14, 1911, Serial No. 614,496. Renewed July 9, 1912. Serial No. 708,512.

To all whom it may concern:

Be it known that I, JESSE PRESCOTT, a citizen of the United States, residing at Webster, in the county of Worcester and 5 State of Massachusetts, have invented an Improvement in Garbage-Incinerators, of which the following description, in connection with the accompanying drawings, is a specification, like letters on the drawings 10 representing like parts.

This invention relates to incinerators or crematories adapted for the burning and disposition of garbage and refuse of various kinds.

15 It is becoming recognized that an apparatus capable of completely burning and disposing of garbage, waste and refuse material where it originates is preferable to the carting of the same away as has heretofore 20 been usual both from a sanitary view point and in an economic aspect, as well as from considerations of convenience.

More particularly my invention is designed as an improvement on former types 25 of incinerators by providing a novel arrangement of flues so constructed as to constitute effective smoke consuming means rendering the apparatus entirely odorless, such flues being also conveniently formed in corners of the inclosing casing, such casing being of angular cross section, forming flue 30 corners at appropriate intervals.

The invention further provides a novel form of center burner combined with a protecting hood for drying out the garbage or 35 refuse, and starting and accelerating the combustion thereof.

Further features of the invention relate to an improved form of dumping grates and 40 garbage holding basket in combination, and in connection therewith an arrangement of doors relative thereto so that the working parts can be easily reached for necessary handling.

45 The above and other detail features of the invention will be fully understood from the following description taken in connection with the accompanying drawings and thereafter pointed out in the appended claims.

50 Referring to the drawings; Figure 1 is a central vertical section through the apparatus on line 1—1 of Fig. 2; Fig. 2 is a horizontal section on line 2—2 of Fig. 1; and Fig. 3 is a detail showing the construction 55 of dumping grates and the burner.

The inclosing shell or casing 1 is rectan-

gular in cross section, preferably and as shown, square. This shell may have any ordinary or preferred cast base 2, and a flue 3 leading from the top thereof. This shell is preferably formed with double, spaced apart walls, the space 4 between such walls being either left as dead air space or filled with suitable insulating material. Fixed transversely in the casing, in the lower portion thereof is a transverse grid or strut 5 and from the corners thereof project struts 5^a on which the garbage basket or holder 6 is supported. This basket is preferably and as shown frusto conical in form being composed of spaced apart slats or bars encircled by rings 7 and 8 at the top and bottom respectively, and by an intermediate ring 9 by which said slats are held in position; it will be understood that this merely typifies 75 any suitable construction of open-work basket which may be used in the practice of my invention. The top of said basket is formed to closely fit the inner walls of the casing, being cut away to conform with the corner 80 flues later described. At a central point the grid 5 is formed with an annular neck 10 internally screw threaded at its top to receive a burner 11. This burner has an externally threaded sleeve 12 to engage the threads of neck 10 opening into a conical cap or hood 85 portion 13, closed except for an annular series of holes 14 drilled in the base passing downward and outward in a circle at some little distance from the inlet collar 12. The 90 cap or hood 13 which thus serves as a protector for the burner has an extension or shroud 15 extended downward from the burner base terminating in an outwardly flared rim 16. The top of this hood is shown 95 extended in a squared head 17 which may be engaged by a wrench for unscrewing the combined burner and hood to remove the same. The fuel supply to the burner is from a suitable supply pipe 18 entering the casing at 19 with a suitable mixer 20 at this point, extending thence by pipe 21 up into the neck 10 for delivery to the burner, whose holes are opposite the grate-spaces of the circular grate or basket 6.

The bottom of the garbage basket or holder 6 is formed with opposite drop grate sections 22, 23, pivoted at their ends at 24, to ears 25 on grid 5. These grate portions are adapted to be engaged from underneath 110 at points remote from their pivots by slideable rods 26, 27, whereby they are supported

in horizontal operative position. These rods 26, 27, are slidably supported in the casing and have handles 28 extending therefrom so that upon the withdrawal of said rods 5 the grates may swing downward permitting the basket to be emptied into an ash pan 29 when the contents are completely burned. The drop sections 22, 23, have radial openings 30 therein, and the holes 14 in the 10 burner are so formed that each will correspond with and be directly opposite one of the radial openings 30, so that the tongues of flame projected downward and outward from the openings 14 will quickly work their 15 way through the garbage mass at the bottom of the basket and make an outlet around the bottom of the basket and up the conical sides thereof.

Across the corners of the casing, plates 31 20 are fixed, these extending from a point at the lower portion of the basket up to near the top of the casing. The corner flues thus formed are closed at the bottom by any suitable closure caps 32 and open at the top. Relatively small openings 33 into said flues 25 are formed just below the top of the basket and a series of other openings 34 preferably and as shown in the form of vertical slots are disposed at intervals in the height of 30 said flues above the basket top. A dumping hopper door 35, for the admission of the garbage or other material to be incinerated, is pivoted at 36, the door portion 37 thereof having a suitable handle 38, fixed thereto. Registering openings are formed in the inner and outer casing members whereby the basket, burner and other working parts of 35 the device are readily accessible whenever necessary. These openings are closed by any suitable doors, those shown at 39 and 40 being hinged to swing on vertical pivots on the casing.

In the practice of my invention most combustible forms of waste may be incinerated 45 merely by dumping the same into the basket without the use of burner 11. For the consumption of ordinary garbage, vegetable refuse, etc., for which my apparatus is especially intended, however, the mass filling the 50 basket 6 would be mostly or wholly incom- bustible by itself, and to accelerate and insure the complete combustion thereof, gaseous or volatile fluid such as gasolene is supplied through pipe 18 to the burner 11. 55 This upon being ignited causes the projection of tongues or jets of flame downward and outward as guided by the shroud 15, 16 of the hood 13, which quickly eats a way through the bottom portion of the garbage 60 mass, so that the flame and heated currents emerge through the openings 30 to pass along to the periphery of the bottom, thence up the flaring outsides of the basket to finally enter the flue inlets 33. It is to be 65 observed that in this passage of the flame

in the initial steps of combustion, the well known tendency of heat and flame to rise, will cause it to impinge on, dry out and eat into the garbage mass all along the slotted bottom of the basket-like grate and likewise up the flaring slatted sides thereof. The flue inlets 33 being relatively small, the flame and heated currents from the burner constantly seek other flue entrances and as the garbage mass dries out and begins to be 70 consumed, increasing vent for the gaseous products of combustion will be found through the slatted sides of the basket, through the garbage mass at the periphery of the basket and thence into the corner flues through the upper slots 34. At the same time the central part of the garbage mass is being rapidly dried out by heat transmitted thereto by the hood 13, which is likewise heated by the annular burner flame. 75 As the operation thus progresses so that the garbage begins to be appreciably consumed, the inner casing and corner flue plates 31 will become heated especially at the lower portions thereof, and the flame passing into 80 the flues at successive points in the height thereof, through the several sets of vertical slots, will cause substantially complete combustion of all combustible gases before their final escape through the chimney flue 3, thus 85 rendering the apparatus entirely odorless in use.

It is to be noted that by reason of the construction including the central burner with its protecting cone cap extending up well 100 into the basket and arranged to direct the flame downward and outward, in conjunction with the upwardly and outwardly flaring openwork basket, and the peripheral corner flues co-operating therewith, as set 105 forth, the heat of the burner is spread up into the center of the garbage mass by means of the conical cap 13, while the flame from the burner is spread outward by the lower rim of this cap and drawn by the flue suction 110 outward and upward along the flaring open sides of the basket so as to impinge on and eat into all portions of the bottom and sides of the garbage mass, the garbage being thus quickly dried out and incinerated. 115 I consider the construction for thus disseminating and spreading the heat and flame within and about all parts of the garbage mass to be an important feature of the invention and I desire to cover the construction for effecting this broadly, as also the special construction whereby the disseminating and spreading of the heat and flame is effected by a central burner and by spaced apart peripheral flues, as disclosed. 120

It is to be further observed that by the disposition of the flues in the corners of the shell or casing, the interior of the receptacle is left entirely unobstructed so that a large quantity of garbage can be received, and 125 130

particularly so that it will be more evenly laid in the basket; this latter is an important feature since for the proper operation of the flame in drying out and facilitating the combustion of the garbage mass, it is desirable that such mass be disposed as uniformly as may be in the receptacle so that flame and heated currents will not eat a way through and find an unobstructed outlet at one side before the other parts of the mass are attacked in like degree. In former apparatus of this kind the presence of transverse flues within the garbage receptacle has led to the uneven disposition of the garbage therein with the resulting objections just noted. Further this arrangement of flues can be much more cheaply constructed than when separate conduits are formed therefor. The construction of a central burner with the flaring protecting hood thereover as one element is particularly advantageous, affording an effective heating and drying means extending well up into the garbage mass while serving to direct the flame and heated currents downward and outward in line with the grate slots, as requisite for the proper operation of the apparatus. Further this construction enables the burner and hood to be quickly and easily removed whenever necessary.

The construction of a frusto conical basket with drop bottom grates and with the doors opening opposite thereto, enables the garbage and ash residue to be manipulated as may be necessary and disposed of with facility.

Having described my invention, what I claim as new and desire to secure by Letters Patent is as follows:

1. A garbage incinerator, comprising a vertically extending casing angular in cross section, means for holding garbage therein composed of a grate in the lower part thereof of having an upstanding open-work holder portion spaced away from a part of the walls of the casing, means for dividing off corner spaces of said casing to form flue deliveries, and a burner for gaseous fuel mounted in the lower part of the casing to direct flame to encompass the garbage mass, the upstanding open-work holder portion and the corner flues being arranged and having provision to insure vent for the products of combustion of said burner when the casing is filled with garbage.

2. A garbage incinerator, comprising an upright casing angular in cross section, garbage holding means in the lower part thereof consisting of a grate having an open-work upstanding holder spaced away from the casing walls at its lower portion, but substantially fitting said walls at its top, means for forming flues in the corners of said casing, and a gas burner mounted and arranged to direct flame to encompass the garbage

mass in the casing, said corner flues having openings below the top of said upstanding portion whereby vent passage up through the casing is insured when it is filled with garbage.

3. A garbage incinerator, comprising an upright casing angular in cross section, means for partitioning off the corners of said casing to form flues, a garbage holder in the lower part of said casing having an outwardly flaring upstanding holder spaced away from the casing walls for most of its height, but substantially fitting said walls at its top, and a central burner for gaseous fuel arranged to spread and direct flame to encompass the garbage mass, said corner flues having openings into the space below the top of said upstanding holder for the purpose stated.

4. A garbage incinerator comprising a casing, a flue extending vertically along a side thereof, a flaring openwork holder for matter to be burned in the lower part of said casing, and means for producing heat centrally of the casing and directing the same outward to pass upward around said flaring openwork holder, there being a passage to permit heated currents to pass thence up said flue, whereby heated currents are caused to directly attack all parts of the garbage mass simultaneously.

5. A garbage incinerator comprising a casing, a central burner mounted in the lower portion thereof and having provision to direct flame downwardly and outwardly, a garbage holder with flaring openwork sides extending around said burner, whereby flame and heated currents may pass from the bottom upward along said openwork sides to impinge on all parts of the garbage mass, and flue means opening near the top of said garbage holder to promote the movement of flame as described.

6. A garbage incinerator comprising a casing, a central burner mounted in the lower part thereof having provision to direct flame annularly downward and outward, a holder for matter to be burned having a grate mounted below said burner with openings through which flame may pass, and an upper open-work portion flaring outwardly to the walls of the casing.

7. A garbage incinerator comprising a casing, a burner mounted in the lower part thereof having a circular series of openings arranged to produce a downwardly and outwardly projected annulus of flame and a tapering protecting hood thereover, and a holder with flaring openwork sides for matter to be burned mounted in said casing to encircle said burner, whereby the heat is disseminated within and the flame made to encompass the garbage mass.

8. A garbage incinerator comprising a casing, a burner mounted in the lower part

125

130

thereof having openings to direct flame annularly downwardly and outwardly, a garbage holder encircling said burner with radially extending openings therein, and a 5 tapering hood having a part extending downward and outward below the burner holes to aid in directing the flame around the garbage mass so as to encompass the same.

10. 9. A garbage incinerator comprising a casing, a burner mounted in the lower part thereof having provision to create a downwardly and outwardly projected annulus of flame and having a conical protecting hood, 15 and a holder for matter to be burned encircling said burner having slotted sides flaring outwardly upward to the walls of said casing, and peripheral flues arranged to promote spreading of the flame over the 20 garbage mass from said burner.

10. A garbage incinerator comprising a casing, a burner mounted in the lower part thereof having provision to create downwardly and outwardly projected flame, an 25 open-work holder for matter to be burned spaced away from the casing wall and flaring upwardly outward with its top extending to the walls, and a vertical flue at a side of said casing having an opening just below the top of said holder.

11. A garbage incinerator comprising a casing, a central burner in the lower part thereof having provision to direct the flame downwardly and outwardly, an encircling 35 grate on which matter to be burned may rest, a flaring openwork holder for garbage extending outward to fit the casing walls, and a flue extending upward in the casing constructed to receive heated currents only 40 after passage in contact with the garbage mass.

12. A garbage incinerator comprising a casing, a burner arranged in the lower part thereof, a holder for matter to be burned 45 spaced away from the casing walls and flaring upwardly outward with its top extending to the walls of the casing, and a flue extending vertically in the casing at a side thereof having an opening just below the top 50 of said holder, and other openings into the casing above said holder.

13. A garbage incinerator comprising a casing, angular in cross section, a burner mounted in the lower part thereof, an open- 55 work holder for matter to be burned spaced away from the casing walls and flaring upwardly outward with its top extending to the walls, flues formed in the corners of said casing having openings just below the top 60 of said holder, and other openings at intervals above the top thereof.

14. A garbage incinerator comprising a casing, a burner mounted in the lower part thereof having provision to direct flame 65 downward and outward, an open-work

holder for matter to be burned spaced away from the casing walls and encircling said burner flaring upwardly outward with its top extending to the walls of the casing, a flue vertically arranged at a side of the casing having an opening just below the top 70 of said holder, and other openings above said holder.

15. A garbage incinerator, comprising a vertically extending casing, means for holding garbage or the like in the lower part thereof, said means having an open construction to permit direct action of the flame on both the bottom and sides of the garbage mass, a central burner extending up into 80 the garbage holding space of said casing, arranged to spread flame outward, and a peripheral flue construction having provision for an unobstructed opening laterally adjacent said garbage holding means and near the periphery thereof whereby heat is both disseminated centrally up within the garbage mass and the flame caused to spread outward over the periphery thereof.

16. A garbage incinerator comprising a 90 casing, a burner removably mounted centrally in the lower part thereof having provision to direct flame downwardly and outward, an open-work holder for matter to be burned having sides flaring upwardly outward to the walls of the casing the lower portion of said holder being spaced away from the casing walls to leave a space for heat circulation, and a bottom grate with radial openings, said grate being formed to 95 be dropped downward at will to permit escape of the ash residue.

17. A garbage incinerator comprising a casing, a garbage holder mounted in the lower part thereof having slotted, upwardly 105 flaring sides, a central burner having a cover extending up within said holder and arranged to direct flame outwardly, and flues at the periphery of said casing having openings adjacent an upper portion of said holder and near the periphery thereof whereby heat is disseminated at the center of the garbage mass by conduction and flame spread to encompass the bottom and sides of the garbage mass in passing to said flue openings.

18. An apparatus of the kind described, comprising an upright angular casing having corner flues formed therein, means for holding garbage or the like in a lower portion of said casing, comprising a bottom 110 grate and a peripheral vertical grate spaced apart annularly from the walls of the casing, the annular space thus formed opening upward into said corner flues, the parts being arranged to provide means for preserving 115 circulation passage outside of the garbage from the bottom of the peripheral grate to the upper end of said corner flues above the peripheral grate, when the apparatus is 120 filled with garbage.

19. An apparatus of the kind described, comprising an upright rectangular casing having vertical corner flues formed therein, a holder in the lower portion of said casing 5 extending therearound and spaced apart from the walls thereof, a gas burner in the lower portion of said holder, and means for maintaining circulatory passages outside of the holder from the bottom of the latter up 10 through the annular spaces thus formed and

directly into said corner flues when the apparatus is filled with garbage.

In testimony whereof, I have signed my name to this specification, in the presence of two subscribing witnesses.
